UNITED STATES PATENT OFFICE.

FRANK F. SMITH, OF NEWARK, NEW JERSEY.

TRANSOM-ADJUSTING DEVICE.

970,656.

Specification of Letters Patent. Patented Sept. 20, 1910.

Application filed January 28, 1909. Serial No. 474,813.

To all whom it may concern:

Be it known that I, FRANK F. SMITH, a citizen of the United States, and a resident of Newark, in the county of Essex and 5 State of New Jersey, have invented certain new and useful Improvements in Transom-Adjusting Devices, of which the following is a specification.

My invention relates to means adapted to 10 limit the extent of opening windows of the reversible pivoted sash type, and particularly to automatically closing, fire-proof windows; and it has for its object to simplify such means, and to render the same positive 15 in its action.

I attain these objects by the devices illustrated in the accompanying drawings in which—

Figure 1 is a partial front elevation, of 20 a window frame and sash provided with my improved device. Fig. 2 is a partial view looking toward the jamb viz. in the direction of the arrow in Fig. 1 and showing the sash in opened position.

Similar characters of reference designate 25 corresponding parts throughout the several views.

Referring to the drawings, 10 designates a sash frame of the usual sheet-metal construction common to fire-proof windows. 30 In this frame is fitted a sheet-metal sash 11 provided with the usual wired-glass panes. This sash is pivotally secured to the frame 10 by means of the sash-brackets 12, adapted 35 to be secured at each side of the inner face of the sash, said brackets having trunnions or pivots 13 working in bearings in stop-plates 14 and reinforcing plates 15 secured to the frame 10. The sash 11 is so adjusted 40 as to be self closing by gravity, and the window is held open in the usual manner by some suitable means such as a chain or the like (not shown).

Pivotally secured to the sash 11, and 45 usually to only one side of the sash, is a depending, gravity latch-piece 16 whose lower end 17 engages, when the said sash has swung open to a predetermined extent, with the stop 18 of stop-plate 14, which 50 plate is secured to the inner face of the frame 10 as shown. This latch-piece is forked at its upper end and is pivoted to the sash-bracket 12 by means of a pin 19 journaled in a bearing 20 through a lug 21 of the said sash-bracket.

The latch-piece 16 gravitates at all times

automatically into alignment with the stop 18 so that when the sash 11 is swung as in Fig. 2 to open the window, said latch-piece is thereby lowered until its end 17 comes in contact with the stop 18 which thereupon 60 prevents further swinging or pivoting of the sash. Before causing the sash to swing inwardly until the latch-piece 16 shall engage with the stop 18, the said latch-piece 65 may be pivoted by hand to avoid engagement with the stop 18, whereby the said sash may be swung inwardly beyond the limit imposed by said stop, and reversed, as for 70 washing purposes.

It will be noted that the member 16 curves or projects laterally (see Fig. 1) so as to overlie the stop 18, whereas the latter does not project laterally, but on the contrary is kept within the edge of the sash opening of 75 the window frame so that it does not strike the sash and so interfere with its pivoting.

Of course, it will be understood that the invention is not to be limited to the precise form of sash stop shown, as for example, to 80 the precise laterally-curved pivoted member 16 shown, nor to a sash which on opening swings inwardly at the top as distinguished from swinging inwardly at the bottom, nor to the sash stop with the pivoted member on 85 the sash and the fixed stop on the frame, because it is apparent that these conditions might be reversed, also that other changes and modifications could be made which would still be within the spirit of the invention, and therefore it is the intention to 90 cover not only the precise form shown but also any and all equivalent modifications.

I claim:

1. In a window of the reversible pivoted 95 sash type: a stop secured to the frame of said window; and a vertically depending, gravity latch-piece pivotally secured to the sash of said window, the lower end of said latch-piece swinging freely and engaging 100 with the stop after the sash has swung open to a predetermined extent.

2. In combination with a window frame having a reversible sash pivoting about an intermediate transverse axis, a sash stop 105 acting between said frame and sash consisting of a laterally projecting gravity member 16 on the one acting against a stop 18 on the other, the gravity member being supported on the one by a pivot 19 to gravitate 110 at all times automatically into alignment with the stop and being independent of said

stop for its working, said gravity member and stop coming into contact when the sash has been pivoted partly open thereby preventing its further opening, and said gravity member being pivotable out of alinement with the stop to permit reversal of the sash.

3. In combination with a window frame having a reversible sash pivoting about an intermediate transverse axis, a sash stop 10 acting between said frame and sash consisting of a gravity member on the one acting against a stop on the other, the gravity member being pivotally supported on the one to gravitate at all times automatically 15 into alinement with the stop and being independent of said stop for its working, said gravity member and stop coming into contact when the sash has been pivoted partly open thereby preventing its further opening, 20 and said gravity member being pivotable out of alinement with the stop to permit reversal of the sash.

4. In combination with a window frame

having a reversible sash pivoting about an intermediate transverse axis, a sash stop 25 acting between said frame and sash consisting of a gravity member on the one acting against a stop on the other, the gravity member being movably supported on the one to gravitate at all times automatically 30 into alinement with the stop and being independent of said stop for its working, said gravity member and stop coming into contact when the sash has been pivoted partly open thereby preventing its further opening, 35 and said gravity member being movable out of alinement with the stop to permit reversal of the sash.

Signed at Newark in the county of Essex and State of New Jersey this 26th day of January A. D. 1909.

FRANK F. SMITH.
